PLAYGROUND SWING

Robert S. Wormser, Hillsdale, Mich., assignor to Game-Time, Inc., Litchfield, Mich., a corporation of Michigan

Filed Mar. 20, 1968, Ser. No. 11,073

Term of patent 14 years

Int. Cl. D21—03

U.S. Cl. D34—5

FIG. 1

FIG. 1 is a front elevational view of a playground swing in accord with my new design, the rear being identical thereto,

FIG. 2 is an elevational side view, the opposite side being identical thereto, and

FIG. 3 is a top plan view of my design.

The dominating features of the design are shown in the drawing in full lines.

I claim:

The ornamental design for a playground swing, substantially as shown and described.
